APPARATUS FOR PRODUCING VIBRATING
LIGHT EFFECTS

Jozsef König, Budapest, Hungary

Application May 11, 1935, Serial No. 21,051
In Hungary February 20, 1934

6 Claims. (Cl. 40—34)

The subject of the present invention is an apparatus for producing vibrating light effects which is particularly suitable for advertising purposes and can be used in daylight as well as in artificial light.

5 The invention is illustrated by way of example in the accompanying drawing, in which

Figure 1 is a front elevation,

Figure 2 a part side elevation of a detail,

10 Figure 3 a side elevation of the apparatus, partly in section,

Figure 4 is a section through a part of the detail shown in Fig. 2.

15 Referring to the constructional examples illustrated in the drawing, the apparatus comprises a clockwork mechanism 2 provided in a casing 1.

For this purpose an ordinary alarm clock movement can be employed which by means of the spindle 3' engages in a socket 4 which is pro-

20 vided with a plurality of arms 5 carrying a reflector 6. The drive of the spindle 3' is preferably taken off from the small bottom wheel 17 of the clockwork mechanism in such a manner that two gear wheels 7 and 3 are added, the one being

25 provided on a spindle 7 and the other on the spindle 3' so as to drive the latter with a step-up transmission ratio.

The reflector 6 which, for example, consists of an aluminium sheet or foil is provided with a plurality of depressions 8. In front of the reflector is arranged a furrowed glass disc 9 which is provided with furrows extending in two different directions. Instead of a furrowed glass plate, a surface can be employed having a plurality of adjacent prisms. On the disc 9 is situated a sheet

30 of paper 10 bearing the text, which disc in turn is covered by a glass plate 11. The two plates 11 and 9 are secured by means of three angle pieces 12 distributed around the periphery of the casing and by means of a ring 13 by means of screws 14.

40 The entire apparatus can be placed upright with the aid of a stirrup 15 or may be hung up on a wall by means of a hook 16.

The mode of operation of the apparatus is as follows:—

45 The light passing through the discs 11 and 9 is broken by the disc 9 and caused to impinge upon the reflector 6 in the most diverse directions. The reflector 6 rotates and in turn projects the light back again in various continually varying angles.

50 By this means a vibrating light effect is produced upon the front side of the apparatus. In the case of the illustrated constructional example one has the impression of mercury being moved behind the plate 11 and along the strokes of the text.

55 The transparent paper 10 bearing the inscrip-

tions can of course also be coloured and it is also possible to provide the inscriptions directly upon the reverse side of the cover glass 11 instead of upon a separate sheet of paper or to apply the inscriptions upon some other material. 5 The apparatus could also be devised in such a manner that behind the cover disc 11 a disc bearing the inscriptions or a sheet of paper or other material provided with the advertising pictures can be exchangeably provided. In order to produce a coloured light effect, the reflector or the discs 9 and 11 may be made in one or more colours. The same effect could also be obtained by making the disc 9 of a different formation. The drive of the reflector can also be effected by 10 means of an electro-motor instead of by means of a clockwork mechanism. The important point is only that the light is projected by it in the most diverse directions upon the reflector.

15 The advantage of the apparatus above described consists in this that it is exceedingly cheap to manufacture and does not involve any operation costs. The optical action is quite considerable and special since it attracts attention to itself by the continuous vibration of the light. 20

I claim:

1. Apparatus for producing vibrating light effects, more particularly for advertising purposes, comprising in combination a transparent surface formed of a plurality of prismatic bodies situated 30 next to one another, a movable reflector positioned permanently parallel to said transparent surface and having a plurality of reflecting surfaces and actuating means for moving the reflector relatively to the transparent surface and 35 in a plane parallel to said transparent surface.

2. Apparatus for producing vibrating light effects, more particularly for advertising purposes, comprising in combination a transparent glass sheet furrowed in different directions to form a 40 plurality of prismatic bodies situated next to one another, a movable reflector having a plurality of depressions in its reflecting surface and actuating means for moving the reflector relatively to the transparent glass sheet. 45

3. Apparatus for producing vibrating light effects, more particularly for advertising purposes, comprising in combination a transparent surface advertising means at one side of said surface, said transparent surface being formed of a plurality of 50 prismatic bodies situated next to one another, a movable reflector having depressions in its reflecting surface and actuating means for moving the reflector relatively to the transparent surface. 55

4. Apparatus for producing vibrating light effects, more particularly for advertising purposes, comprising in combination a transparent surface formed of a plurality of prismatic bodies situated next to one another, said transparent surface having advertising means at one side thereof which at the parts where the vibrating light effects are to be shown is transparent, a movable reflector having a plurality of depressions in its reflecting surface and actuating means for moving the reflector relatively to the transparent surface.
5. Apparatus for producing vibrating light effects, more particularly for advertising purposes, comprising in combination a transparent surface formed of a plurality of prismatic bodies situated next to one another, a movable reflector having a plurality of reflecting surfaces and actuating
- means for moving the reflector relatively to the transparent surface, the said movable reflector comprising a metal sheet having a plurality of the depressions therein.
6. Apparatus for producing vibrating light effects, more particularly for advertising purposes, comprising in combination a casing having means for enabling it to be set up, a transparent surface formed of a plurality of prismatic bodies situated next to one another in said casing, a glass disc 10 having advertising matter thereon in said casing, a movable reflector having a plurality of reflecting surfaces situated in the casing behind said transparent surface and glass disc and actuating means in the casing for moving the reflector relatively to 15 the transparent surface and glass disc.
